CLAIM

The ornamental design for a sports ball as shown and described.

DESCRIPTION

FIG. 1 is a bottom, front, right side perspective view of a sports ball, according to a first embodiment;
 FIG. 2 is a top, front, right side perspective view of the design of FIG. 1;
 FIG. 3 is a top, rear, left side perspective view of the design of FIG. 1;
 FIG. 4 is a top, rear, right side perspective view of the design of FIG. 1;
 FIG. 5 is a right side elevation view of the design of FIG. 1;
 FIG. 6 is a left side elevation view of the design of FIG. 1;
 FIG. 7 is a rear elevation view of the design of FIG. 1;
 FIG. 8 is a front elevation view of the design of FIG. 1;
 FIG. 9 is a top plan view of the design of FIG. 1; and
 FIG. 10 is a bottom plan view of the design of FIG. 1.
 FIG. 11 is a bottom, front, right side perspective view of a sports ball, according to a second embodiment;
 FIG. 12 is a top, front, right side perspective of the design of FIG. 11;
 FIG. 13 is a top, rear, left side perspective view of the design of FIG. 11;
 FIG. 14 is a top, rear, right side perspective view of the design of FIG. 11;
 FIG. 15 is a right side elevation view of the design of FIG. 11;
 FIG. 16 is a left side elevation view of the design of FIG. 11;

FIG. 17 is a rear elevation view of the design of FIG. 11;
 FIG. 18 is a front elevation view of the design of FIG. 11;
 FIG. 19 is a top plan view of the design of FIG. 11; and
 FIG. 20 is a bottom plan view of the design of FIG. 11.
 FIG. 21 is a bottom, front, right side perspective view of a sports ball, according to a third embodiment;
 FIG. 22 is a top, front, right side perspective view of the design of FIG. 21;
 FIG. 23 is a top, rear, left side perspective view of the design of FIG. 21;
 FIG. 24 is a top, rear, right side perspective view of the design of FIG. 21;
 FIG. 25 is a right side elevation view of the design of FIG. 21;
 FIG. 26 is a left side elevation view of the design of FIG. 21;
 FIG. 27 is a rear elevation view of the design of FIG. 21;
 FIG. 28 is a front elevation view of the design of FIG. 21;
 FIG. 29 is a top plan view of the design of FIG. 21; and
 FIG. 30 is a bottom plan view of the design of FIG. 21.
 FIG. 31 is a bottom, front, right side perspective view of a sports ball, according to a fourth embodiment;
 FIG. 32 is a top, front, right side perspective view of the design of FIG. 31;
 FIG. 33 is a top, rear, left side perspective view of the design of FIG. 31;
 FIG. 34 is a top, rear, right side perspective view of the design of FIG. 31;
 FIG. 35 is a right side elevation view of the design of FIG. 31;
 FIG. 36 is a left side elevation view of the design of FIG. 31;
 FIG. 37 is a rear elevation view of the design of FIG. 31;
 FIG. 38 is a front elevation view of the design of FIG. 31;
 FIG. 39 is a top plan view of the design of FIG. 31; and
 FIG. 40 is a bottom plan view of the design of FIG. 31.
 FIG. 41 is a bottom, front, right side perspective view of a sports ball, according to a fifth embodiment;
 FIG. 42 is a top, front, right side perspective view of the design of FIG. 41;
 FIG. 43 is a top, rear, left side perspective view of the design of FIG. 41;
 FIG. 44 is a top, rear, right side perspective view of the design of FIG. 41;
 FIG. 45 is a right side elevation view of the design of FIG. 41;
 FIG. 46 is a left side elevation view of the design of FIG. 41;
 FIG. 47 is a rear elevation view of the design of FIG. 41;
 FIG. 48 is a front elevation view of the design of FIG. 41;
 FIG. 49 is a top plan view of the design of FIG. 41; and,
 FIG. 50 is a bottom plan view of the design of FIG. 41.
 The broken lines immediately adjacent to the shaded areas depict the bounds of the claimed design, while all other broken lines are directed to the environment. The broken lines form no part of the claimed design. The gray in this application is a drafting convention used to show contrast with adjacent surfaces.
